STENCIL-MOISTENING APPARATUS

Harmon P. Elliott, Watertown, Mass.

Application February 16, 1949, Serial No. 76,817

9 Claims. (Cl. 91--38)

1

This invention relates to improvements in stencil-moistening apparatus and more particularly to apparatus for moistening the stencil tissue of printing stencils preliminarily to type-cutting of a name and address, or other information, in the stencil tissue.

The names and addresses, or other information, which are to be borne by the stencil tissues of printing stencils of the general type employed in addressing machines and other business and statistical machines, are type-cut in the tissues by a typist using a typewriter equipped with special stencil-cutting characters. But, in order to effectively cut a name and address, or other data, in the stencil, the stencil tissue needs to be preliminarily moistened, preferably on that side of the tissue which is to be struck by the type-characters of the typewriter.

It is among the objects of my present invention to provide a relatively small and conveniently portable stencil-moistening apparatus which may rest on any suitable support beside the typist and which is adapted to project a moistened stencil into convenient reach of the typist in response to a mere up-stroke of the typist's hand against an actuator.

Another object is to provide a stencil-moistening apparatus wherein a supply of stencils is held in a stack with the tissue of the lowermost stencil normally resting against a capillary moistening wick, and wherein stencil-projecting means is operable to move the moistened lowermost stencil along a supporting track to a projected pick-off position in response to a relatively slight uplifting of the stack of stencils.

A further object is to provide a stencil-moistening apparatus wherein a supply of stencils is held in a stack above a track, with the lowermost stencil resting on the track and with the tissue of the lowermost stencil engaging a moistening wick, the track being pivotally mounted at one end, and there being means for projecting the lowermost stencil to a pick-off position in response to a movement of the track about its pivot.

It is, moreover, my purpose and object generally to improve the structure and efficiency of stencil-moistening apparatus and especially apparatus for moistening the stencil tissues preparatory to type-cutting of printing characters in the stencil tissues.

In the accompanying drawings:

Fig. 1 is a side elevation of stencil-moistening apparatus embodying features of the invention;

Fig. 2 is a top plan view thereof with the forward portion of a stencil shown dotted in projected pick-off position;

2

Fig. 3 is a cross-sectional view on line 3--3 of Fig. 2, but showing the device in stencil-projecting condition;

Fig. 4 is a top plan view of the stencil track elements with the stencil-projecting slide mounted thereon;

Fig. 5 is a detail elevation of the wick-supporting bracket; and

Fig. 6 is a cross-sectional view of one of the stencils, on an enlarged scale.

Referring to the drawings, a rectangular container 10 is suitably secured on a base 12 whose under side preferably will be provided with protective feet 14, of rubber or the like, to avoid marring of a desk or table on which the base 12 may rest.

Two parallel bars 16 extend along and above the opposite side walls of container 10, they being rigidly connected together at the region of the front of the container by the cross bar 18, and their rear ends being pivotally supported on the rear wall of container 10 by means of shaft 20 which extends through ears 22 on bracket 24 and through depending ears 26 on the bars 16. Bracket 24 is secured to the rear wall of container 10 as by the screws 28.

A stencil holder is indicated generally at 30, it being secured, as at 32, to the upper sides of bars 16, and it is adapted to hold a stack of stencils 34, with the lowermost stencil in the stack resting on the bars 16. Each bar 16 is reduced in thickness at 36, so that the lowermost stencil rests on the reduced thickness portions of the bars, with the longitudinal shoulders 38 (Fig. 4) extending along the side edges of the stencil frame. Hence, the bars 16 constitute rails of a track along whose reduced portions 36 a stencil may move toward the front of the apparatus.

A slide is indicated generally at 40, it being slidably mounted on the bars 16 and having a portion 42 extending across from one bar 16 to the other. Portion 42 has the forwardly facing shoulders 44 thereon arranged and adapted to engage the rear edge of the lowermost stencil, which is resting directly on the reduced thickness portions 36 of bars 16, when the slide 40 is moved forward along bars 16, thereby to project the lowermost stencil a substantial distance forwardly of the stack 34, as best seen at 46 in Fig. 3, and in the top plan view of Fig. 2 wherein the projected stencil is shown in dotted outline.

Slide 40 is operated to project the lowermost stencil in response to a relatively small upward swinging of bars 16. The slide, at each side of the apparatus, has an upstanding ear or lug 48 thereon, and the forward ends of two coil springs

50 are connected respectively to the ears 48 at opposite sides of the apparatus. The rear ends of springs 50 are connected respectively to the rear ends of bars 16, as by means of a hook or eyelet 52 upstanding at the rear end of each bar 16. Hence, the springs 50 constantly bias the slide 40 rearwardly to the limit of its rearward travel, which limit may be determined by stop screws 54 or any other suitable stop means.

A pulley 56 is rotatably mounted forwardly on each bar 16, as by means of a bracket 58 secured to the outer margin of each bar and depending below the plane of the bars. Two separate belts 60 are trained over the respective pulleys, with their rear ends secured respectively to the slide ear 48 at each side of the apparatus, and with their forward ends anchored at 62 low down on the front wall of container 10. Actually, the belts 60 have their anchorages 62 at the opposite laterally projecting ends of a bar 64 which is secured to the front wall of container 10, so that each belt may be generally in a vertical plane.

When it is desired to project a stencil to the pick-off position at 46 in Figs. 2 and 3, the typist merely lifts the forward end of a bar 16, the bars 16 projecting a substantial distance forwardly of the stencil stack for this purpose, and their forwardly projecting portions being reduced in thickness to the thickness of the track portions 36, so that they will not interfere with the forward movement of a stencil. Lifting of bars 16 from their position of Fig. 1 to their position of Fig. 3 will cause slide 40 to have relative motion forward along bars 16 from its position of Figs. 1 and 2 to its position of Fig. 3, and the relative motion will be in opposition to the biasing force of the springs 50. The forward relative motion of slide 40 will cause shoulders 44 of the slide to engage the rear edge of the lowermost stencil in the stack, thereby to project the engaged stencil forward as in Fig. 3. When the bars 16 are released, they drop back to their positions of Fig. 1, and springs 50 return slide 40 to its rearmost position of Figs. 1 and 2. Any suitable stop means, such as screws 65, may limit the forward travel of slide 40.

Moistening of the tissue of each lowermost stencil in the stack 34 is accomplished while the apparatus is in its condition as shown in Fig. 1. As shown in Fig. 3, a capillary wick 66 is supported within container 10 on any suitable supporting frame or bracket 68. The wick 66 is shown as in the form of a sheet of capillary material draped over its support so that substantial portions of the sheet, at opposite sides of the support, hang well down in container 10 which will have a substantial amount of water 70, or other liquid, therein. The elevated portion of the wick will be located so as to be engaged by the tissue of the lowermost stencil in the stack when the apparatus is in its condition of Fig. 1. Hence, prior to each stencil-projecting actuation of the apparatus, the tissue of the lowermost stencil will be in direct engagement with wick 66 which will be constantly wetted by capillary action so long as liquid remains in container 10. And, as each lowermost stencil is projected and removed from the apparatus, another automatically becomes the lowermost stencil with its tissue in moistening contact with wick 66.

It is intended that the patent shall cover, by suitable expression in the appended claims, whatever features of patentable novelty exist in the invention disclosed.

I claim as my invention:

1. In a stencil-moistening apparatus, means for holding a stack of stencils, means providing a track extending under the stack of stencils with the lowermost stencil resting on the track, said lowermost stencil having a tissue portion, moistening means engaging said tissue portion of the lowermost stencil in the stack, thereby to moisten the tissue, means for moving said track and stack of stencils and said means for holding the stack in general direction away from said moistening means, and a slide member on said track slideable in one direction along the track in response to said movement of the track, stack and holding means away from the moistening means, said slide member having means for engaging said lowermost stencil in the course of its said sliding travel thereby to project the lowermost stencil beyond the stack to a pick-off position.

2. In a stencil-moistening apparatus, a container for holding a supply of liquid, a wick supported in said container and constantly wetted by capillary action, a frame pivotally associated with said container and adapted to rest by gravity across the mouth of the container, said frame including a pair of parallel rails, means mounted on said rails for holding a stack of stencils with the lowermost stencil of the stack resting on said rails, each said stencil having a tissue portion and the tissue portion of the lowermost stencil being in engagement with said wick, means for manually moving said frame about its pivot, and means responsive to a said movement of the frame about its pivot for moving the lowermost stencil along said rails to a projected pick-off position.

3. In a stencil-moistening apparatus, a container for holding a supply of liquid, a wick supported in said container and constantly wetted by capillary action, a frame pivotally associated with said container and adapted to rest by gravity across the mouth of the container, said frame including a pair of parallel rails, means mounted on said rails for holding a stack of stencils with the lowermost stencil of the stack resting on said rails, each said stencil having a tissue portion and the tissue portion of the lowermost stencil being in engagement with said wick, means for manually moving said frame about its pivot, a slide member movable along said rails and having means for engaging the lowermost stencil to project it beyond the stack to a pick-off position, and means for moving the slide member along the rails in response to a movement of said pivoted frame about its pivot.

4. In a stencil-moistening apparatus, a container for holding a supply of liquid, a wick supported in said container and constantly wetted by capillary action, a frame pivotally associated with said container and adapted to rest by gravity across the mouth of the container, said frame including a pair of parallel rails, means mounted on said rails for holding a stack of stencils with the lowermost stencil of the stack resting on said rails, each said stencil having a tissue portion and the tissue portion of the lowermost stencil being in engagement with said wick, means for manually moving said frame about its pivot, a slide member slidably mounted on said rails, resilient means biasing the slide to one limit of its sliding travel along the rails, means on the slide for engaging and projecting the lowermost stencil when the slide moves in opposition to its said bias, at least one of said rails projecting forwardly of the stack of stencils and

constituting an actuator for said frame, and means responsive to an actuation of said frame about its pivot for moving the slide member in opposition to its said bias, thereby to project the lowermost stencil to a pick-off position.

5. In a stencil-moistening apparatus, means for holding a stack of stencils with the tissue portions of all of the stencils in registering alignment in the stack, a moistening wick arranged to engage and moisten the tissue portion of the lowermost stencil in the stack, means for moving the stack of stencils and said means for holding the stack in general direction away from said moistening wick, thereby to move the lowermost stencil, whose tissue portion will have been moistened, out of engagement with the wick, and means responsive to said movement of the stack of stencils and its holding means for projecting the lowermost stencil out of the stack to a pick-off position.

6. In a stencil-moistening apparatus, means for holding a stack of stencils with the tissue portions of all of the stencils in registering alignment in the stack, a container below the stack of stencils adapted to hold a supply of liquid, a frame pivotally mounted on the container and including a pair of rails extending in supporting relation to the stack of stencils and said means for holding the stack, with the lowermost stencil resting on the rails, a moistening wick supported within the container and engaging the tissue portion of the lowermost stencil, said frame being movable about its pivot to lift the stack and its holding means and the lowermost stencil away from said wick, a slide member movable along said rails and adapted to engage and move the lowermost stencil along the rails to a projected position, and means for moving the slide to project the lowermost stencil in response to a said movement of the frame about its pivot.

7. In a stencil-moistening apparatus, means for holding a stack of stencils with the tissue portions of all of the stencils in registering alignment in the stack, a container below the stack of stencils adapted to hold a supply of liquid, a frame pivotally mounted on the container and including a pair of rails extending in supporting relation to the stack of stencils and said means for holding the stack, with the lowermost stencil resting on the rails, a moistening wick in the container in moistening engagement with the tissue portion of the lowermost stencil, an actuator on said frame for facilitating manual movement of the frame about its pivot thereby to lift the stack and its holding means and the lowermost stencil away from said wick, and means operable in response to a said movement of the frame for projecting the lowermost stencil partially out of the stack of stencils.

8. In a stencil-moistening apparatus, means for holding a stack of stencils with the tissue portions of all of the stencils in registering alignment in the stack, a container below the stack of stencils adapted to hold a supply of liquid, a frame pivotally mounted on the container and including a pair of rails extending in supporting relation to the stack of stencils and said means for holding the stack, with the lowermost stencil resting on the rails, a moistening wick supported within the container and engaging the tissue portion of the lowermost stencil, a slide mounted on said frame and movable along said rails, resilient means yieldably maintaining the slide in a retracted rearward position, and tensile means connected to the slide and adapted to move the slide forwardly along said rails, in opposition to said resilient means, when said frame is actuated about its pivot, and means on said slide for engaging an edge of the lowermost stencil during a said forward movement of the slide thereby to project the lowermost stencil partially out of the stack of stencils in response to a said movement of the frame about its pivot.
- 10 9. In a stencil-moistening apparatus, means for holding a stack of stencils with the tissue portions of all of the stencils in registering alignment in the stack, a container below the stack of stencils adapted to hold a supply of liquid, a frame pivotally mounted on the container and including a pair of rails extending in supporting relation to the stack of stencils and said means for holding the stack, with the lowermost stencil resting on the rails, said frame normally supporting the lowermost stencil in a generally horizontal plane and being swingable about its pivot to lift the stack and its said holding means thereby to lift the lowermost stencil out of said horizontal plane, moistening means for engaging the tissue portion of the lowermost stencil when the stencil is in its said horizontal plane, and means for projecting the leading portion of the lowermost stencil forwardly in response to a said lifting of the stencil out of said generally horizontal plane.
